UNITED STATES PATENT OFFICE.

HARRY R. MEYER, OF EAST PITTSBURGH, PENNSYLVANIA, ASSIGNOR TO WESTINGHOUSE ELECTRIC & MANUFACTURING COMPANY, A CORPORATION OF PENNSYLVANIA.

CONTROL SYSTEM.

Application filed December 2, 1922. Serial No. 604,503.

To all whom it may concern:

Be it known that I, HARRY R. MEYER, a citizen of the United States, and a resident of East Pittsburgh, in the county of Allegheny and State of Pennsylvania, have invented a new and useful Improvement in Control Systems, of which the following is a specification.

My invention relates to systems of control and it has special relation to the control of air-raised pantographs or other current-collecting devices.

An object of my invention is to provide a system of pantograph control, or the like, utilizing two independent sources of power: one to raise the pantograph and one to hold it in the raised position under predetermined operating conditions.

Another object of my invention is to provide a system of the above-indicated character in which a source of power is utilized to hold the pantograph in a raised position under normal operating conditions, while an independent source of power is employed to hold the pantograph in the raised position upon failure of the other source of power.

In the prior art, it has been the custom to use a storage battery as the sole source of energy to operate a magnet valve which, in turn, controlled a compressed air line to hold a pantograph in engagement with a supply conductor. Under normal conditions, with a coil of sufficient capacity to operate the magnet valve, the battery necessarily had to be of relatively large capacity and required very frequent charging.

In my invention, I make use of a small-capacity low-voltage battery in conjunction with a relatively large magnet coil. The battery functions only on the initial raising of the pantograph and at such times as the pantograph may be passing under a section insulator or when the line current fails. At other times, the magnet valve is suitably energized from the line and, at the same time, a small charge is supplied to the battery.

The accompanying drawing is a diagrammatic view of a control system organized in accordance with the present invention.

Referring to the drawing, the system here shown comprises a supply or contact conductor 1, a movable pantograph 2 being adapted to collect current from conductor 1 to operate the main motors of an electric

locomotive or the like (not shown) in the usual manner. A section insulator 9 of any familiar type is inserted in contact conductor 1.

A pipe or conduit 3, communicating with a fluid-pressure tank 4, conducts air or other fluid medium, under pressure, to any suitable actuating device indicated by 10, in the base 5 of the pantograph 2.

A magnet valve 6, controlled by a coil 7, is connected in the pipe line 3 between the base 5 of the pantograph 2 and the fluid-pressure tank 4.

A battery 8 may be connected in series relation with the coil 7 under conditions to be hereinafter set forth.

A relay device 15 is interposed between the pantograph 2 and the battery 8 for protective purposes to be described below.

The operation of my invention may be set forth as follows: If the locomotive is at rest and the pantograph 2 in its lowered position, a control switch 17 may be closed. A local circuit is thus established from battery 8, through switch 17, the coil 7 of magnet valve 6 and a conductor 11 to battery 8. The coil 7 is thus energized and actuates the valve 6 to allow fluid, under pressure, to flow through pipe 3 to move the pantograph 2 upwardly into engagement with the contact conductor 1.

A circuit is thereupon established from conductor 1, through pantograph 2, a resistor 14, coil 16 of relay device 15 and thence to ground G. The coil 16 is thus energized and actuates the relay device 15 into the illustrated closed position.

A further circuit is then established from conductor 1, through pantograph 2, a resistor 13 and relay device 15 to junction point 12, where the circuit divides, one branch including battery 8 and the other branch including switch 17 coil 7 and conductor 11, a common return circuit to ground G being provided. The battery 8 and coil 7 are thus connected in parallel relation between contact conductor 1 and ground G. The coil 7 is thus normally energized to permit the pantograph 2 to remain in its raised contact-making position, and the battery 8 receives a slight charge from the conductor 1 through resistor 13.

In case the line voltage impressed upon contact conductor 1 should fail or the pantograph 2 should be passing under a section

insulator, such as 9; the coil 7 of magnet valve 6 would become de-energized were it not for the battery 8, which would then automatically continue the energization of coil 7 through the previously traced local circuit, whereby the valve 6 would be maintained in the open position. In this way the pantagraph 2 may be maintained in its contact-making position, irrespective of any failure 10 of line voltage.

The relay device 15 concurrently drops to the open position by reason of the de-energization of coil 16, thus serving to prevent discharge of the battery 8 through the main 15 motors or any auxiliary circuits which may be connected to the pantagraph 2.

Upon resumption of the line voltage upon contact conductor 1, or after the pantagraph has passed under section insulator 9, coil 7 20 and battery 8 are again placed in circuit with conductor 1, as previously described.

By opening switch 17, coil 7 becomes de-energized, valve 6 closes and the pantagraph 2 may be made to assume its lower or inoperative 25 position.

It will be seen that I have provided a simple and efficient system by which the pantagraph, under normal running conditions, is held in its raised or operating position by 30 energy taken from the line and, at the same time, a small charge is supplied to the battery. The battery used may, therefore, be of small capacity and need not be taken out of service for charging. Furthermore, upon 35 failure of line voltage for any reason, the pantagraph is automatically maintained in its contact-making position through the agency of the battery, but delivery of current from the battery through other circuits, 40 such as the vehicle motors, is automatically prevented.

I do not wish to be restricted to the specific circuit connections or arrangement of parts herein set forth; as various modifications 45 thereof may be made within the spirit and scope of my invention. I desire, therefore, that only such limitations shall be imposed as are indicated in the appended claims.

50 I claim as my invention:

1. A control system comprising a stationary contact-member, a movable contact member co-operating therewith, means for holding said members in engagement and independent means for automatically holding said contact members in engagement upon failure of said first mentioned means.

2. A control system comprising a contact conductor, a current collector co-operating 60 therewith, means for holding said current collector in engagement with said conductor, and independent means for automatically holding said current collector in engagement with said conductor upon failure of said 65 first mentioned means.

3. A control system comprising a contact conductor, a fluid-pressure-operated current collector co-operating therewith, a source of fluid pressure, a pipe connecting said source and said current collector, a valve in said pipe, a coil for actuating said valve, means for energizing said coil from said contact conductor when in engagement with said current collector, and independent means for energizing said coil upon failure of said first 75 mentioned means.

4. A control system comprising a contact conductor, a current collector co-operating therewith, a storage battery and a coil connected to said current collector in parallel circuit relation and adapted to be energized by said contact conductor when in engagement with said current collector, and means for opening said circuit and placing said battery in series relation with said coil under other operating conditions of said collector. 80

5. A control system comprising a contact conductor, a fluid-pressure-controlled pantagraph co-operating therewith, a fluid-pressure supply pipe connected to said pantagraph, a valve in said fluid-pressure pipe, a coil adapted to actuate said valve for controlling the actuation of said pantagraph into or out of engagement with said contact conductor, an auxiliary source of energy connected to said pantagraph in parallel relation to said coil and adapted to be energized from said contact conductor when said pantagraph is in engagement therewith, and means for opening the circuit from said pantagraph and placing said auxiliary source of energy in series relation with said coil upon any cessation of voltage upon said pantagraph. 95

6. A control system comprising a stationary contact conductor, a movable current collector co-operating therewith, means adapted to move said current collector into or out of engagement with said contact conductor, and means co-operating with said first mentioned means, under certain emergency conditions only, for holding said current collector and contact conductor in engagement. 100

7. A control system comprising a stationary contact conductor, a movable current collector co-operating therewith, pneumatic means adapted to move said current collector into or out of engagement with said contact conductor, means normally energized from said conductor for maintaining such engagement, and independent means for continuing such energization under abnormal operating conditions of said collector. 110

In testimony, whereof, I have hereunto subscribed my name this 20th day of November 1922.

HARRY R. MEYER.
